Patents LLC(57) **CLAIM**

The ornamental design for a combination mouse pad and laptop wrap, as shown and described.

DESCRIPTION

FIG. 1 is a perspective view of a combination mouse pad and laptop wrap showing my new design; and

FIG. 2 is a front elevation view thereof.

FIG. 3 is a rear elevation view thereof.

FIG. 4 is a left elevation view thereof.

FIG. 5 is a right elevation view thereof.

FIG. 6 is a top plan view thereof.

FIG. 7 is a bottom plan view thereof; and,

FIG. 8 is a perspective view of a folded in use version of the design.
